UNITED STATES PATENT OFFICE.

GEORGE HAWKINS, OF PHILADELPHIA, PENNSYLVANIA, ASSIGNOR TO IVINS DIETZ & METZGER COMPANY, OF PHILADELPHIA, PENNSYLVANIA, A CORPORATION OF PENNSYLVANIA.

DESIGN FOR A CARPET FABRIC.

No. 38,904.

Specification for Design.

Patented Nov. 26, 1907.

Application filed October 9, 1907. Serial No. 396,673. Term of patent 7 years.

To all whom it may concern:

Be it known that I, GEORGE HAWKINS, a subject of the King of Great Britain and Ireland, residing in Philadelphia, Pennsylvania, have invented a new, original, and ornamental Design for a Carpet Fabric, of which the following is a specification.

The figure in the accompanying drawing is a face view of a piece of carpet fabric showing my new design.

I claim:

The ornamental design for a carpet fabric, as shown.

GEORGE HAWKINS.
